United States Patent Office

Des. 221,625
Patented Aug. 31, 1971

221,625

PACKAGING CUP

Alfred W. Kinney, Kansas City, Mo., and Frederick P. Marshall, Park Forest, Ill., assignors to Phillips Petroleum Company

Filed Feb. 5, 1970, Ser. No. 21,292

Term of patent 14 years

Int. Cl. D9—99

U.S. Cl. D9—220

FIG. 1

FIG. 2

Des. 221,625

PAGE 2

FIG. 3

FIG. 4

FIG. 1 is a perspective view of a packaging cup showing our new design;

FIG. 2 is a side elevational view, partly in cross section, of the packaging cup of FIG. 1; and

FIG. 3 is a bottom plan view thereof on an enlarged scale.

We claim:

The ornamental design for a packaging cup, as shown.
